UNITED STATES PATENT OFFICE.

CARL F. O. NORDIN, OF NEW YORK, N. Y.

HOLDER FOR ARTICLES WHILE BEING HEATED.

SPECIFICATION forming part of Letters Patent No. 309,402, dated December 16, 1884.

Application filed February 23, 1884. (No model.)

To all whom it may concern:

Be it known that I, CARL FREDERICK OSCAR NORDIN, a subject of the King of Sweden, and a resident of the city, county, and 5 State of New York, have invented certain Improvements in Holders for Articles while being Heated, of which the following is a specification.

My invention relates to a device for holding 10 articles to be heated—as shoemakers' polishing-irons, for example—over a burner. It is primarily designed for use in connection with gas-jets, and it comprises a means for securing a holder shelf or platform to its stem, whereby 15 it may be readily detached, and a peculiarly-constructed clamp for securing the stem to the gas bracket or pipe. The stem is also adapted to be screwed into a bench or table when a lamp is used for heating.

20 In the drawings which serve to illustrate my invention, Figure 1 is a side elevation of my holder and its clamp shown as secured to a gas-bracket. Fig. 2 is a plan of the same. Fig. 3 is a rear or edge view of the clamp. 25 Fig. 4 is a front view of the upper end of the stem, showing the tapered dovetail for attaching the platform. Fig. 5 illustrates the construction of the clamp, being a face view and a cross-section of one-half of the same. Fig. 30 6 illustrates the use of my holder with a lamp for heating.

Referring to Figs. 1 to 5, A represents a 35 gas bracket or pipe, and B a burner-tip on same. C is the stem of the holder, and D is the platform. This form of platform or shelf is designed especially to hold shoemakers' polishing-irons. At its upper end the stem C is provided with a beveled or tapered dovetail, a, which is arranged to engage a corresponding dovetail recess at b in the edge of D. The dovetail a is inserted in the recess b from below, and when the platform is pressed down the taper of the dovetail causes it to fit snugly and hold the platform firmly. Platforms of 40 different shapes and sizes may be used, and one may be readily substituted for the other without removing the stem from the clamp. The clamp E is composed of two like disks, c c, which have raised flanges d. The disks are 45 connected and the clamping effected by an

axial thumb-screw, e, which passes through one disk and screws onto the other. Each disk has two oppositely-arranged V-shaped recesses, g, in its raised rim. In the recesses or notches g in one disk rests the gas pipe or 55 bracket A, and in the recesses in the other disk rests the stem C. By means of the screw e the disks are caused to clamp the stem and pipe together and hold them firmly. The stem and pipe do not cross the disks diametrically, 60 as room must be left for the screw. The position of the clamping notches is clearly shown in Figs. 3 and 5. It will be seen that the stem C may be set at any angle with the gas-pipe that may be desired, and the stem may also 65 be turned on its axis so as to bring either end of the platform over the gas-jet. Where it is not convenient to use a gas-jet, the stem C may be screwed into a bench or board and a lamp be arranged under the platform, as illustrated 70 in Fig. 6. To effect this the end of the stem is or may be provided with a screw, h. If the stem is not made of the proper metal for a screw, the screw h may be cast in it. It may in some cases be cut directly on the stem, how- 75 ever.

My clamp E may be employed for securing the stem of the holder to the gas-pipe when the stem is not made detachable from the platform, and I contemplate using it with holders 80 of this character.

The stem C may be of any length, and the parts may be made of any suitable material. The gas-pipe A may pass through the clamp below the screw e or above it. In Figs. 1 and 85 3 it is shown as passing above the screw.

I am aware that a bracket for supporting an article to be heated has been secured removably to a vertical wall by means of a "key-hole" in the bracket-plate, arranged to engage 90 a headed pin or tack driven in the wall; and I am also aware that a reflector has been provided with a tongue to engage keepers in a fixed part, to form a securing device for said reflector. These constructions I do not claim, 95 as they are very old and have been applied in numerous ways. My construction differs materially from these. I employ a tapered dovetail recess in the platform, and a tapered dovetail on the holder, which wedges tightly 100

into the recess. In addition to this I provide means for holding the stem in its proper position with respect to the burner. The dovetail and recess are of course interchangeable.

5 Either may be on the stem.

Having thus described my invention, I claim—

1. In a holder for the purposes described, the combination of the platform D, provided 10 with a tapered dovetail recess at 'b', and the stem C, provided with a tapered dovetail 'a' to fit the recess in the platform, and means, substantially as described, for securing the stem in its proper position with respect to the burner, substantially as set forth.

2. In a holder for the purposes described, the combination, with the stem and platform, of the clamp E, for securing the stem of the holder to a gas-pipe, constructed substantially 20 as herein set forth.

3. In a holder for the purposes described,

the combination of the platform provided with a tapered dovetail recess, the stem provided with a tapered dovetail to fit and wedge into said recess in the platform, and the clamp, 25 constructed substantially as described, for securing the stem in position with respect to the burner, as set forth.

4. The combination, with the clamp E, of the platform D, provided with a tapered dove- 30 tail recess, and the stem C, provided with a tapered dovetail constructed to fit and wedge into said recess, and with a screw, 'h', whereby the stem may, if desired, be screwed into a bench or board, as set forth.

In witness whereof I have hereunto signed my name in the presence of two subscribing witnesses.

CARL F. O. NORDIN.
